CLAIM

The ornamental design for a bowl for pet and human foodstuff and drinkable liquids, as shown and described.

DESCRIPTION

FIG. 1 is a side view of the bowl.

FIG. 2 is a top view of the bowl.

FIG. 3 is a top perspective view of the bowl; and,

FIG. 4 is a bottom perspective view of the bowl.

The dot-dash broken lines represent the bounds of the claim and form no part of the claimed design.

1 Claim, 2 Drawing Sheets
